GUN SIGHTING TELESCOPE

Paul A. Hoogesteger, Brighton, and Richard L. Pitchford, Brockport, N.Y., assignors to Bausch & Lomb Incorporated, Rochester, N.Y., a corporation of New York

Filed Sept. 21, 1961, Ser. No. 66,793

Term of patent 14 years

(Cl. D57—1)

FIG. 1 is a perspective view of a gun sighting telescope looking at the eyepiece end thereof and showing our new design.

FIG. 2 is an end view of said telescope looking at the objective end.

FIG. 3 is an enlarged sectional view taken on the line 3-3 of FIG. 1, and

FIG. 4 is an enlarged sectional view taken on the line 4-4 of FIG. 1.

The side not shown has substantially the same appearance as the side shown.

We claim:

The ornamental design for a gun sighting telescope, substantially as shown and described.
